UNITED STATES PATENT OFFICE.

DARWIN B. CLEVELAND, OF CLEVELAND, OHIO.

METHOD OF MAKING CANNON.

1,258,188.

Specification of Letters Patent.

Patented Mar. 5, 1918.

Application filed March 8, 1917. Serial No. 153,257.

To all whom it may concern:

Be it known that I, DARWIN B. CLEVELAND, a citizen of the United States, residing at Cleveland, in the county of Cuyahoga and State of Ohio, have invented a certain new and useful Improvement in Methods of Making Cannon, of which the following is a full, clear, and exact description, reference being had to the accompanying drawings.

The object of this invention is to provide for the cheap and rapid manufacture of cannon, especially of comparatively small sizes. My process produces the cannon body from a billet by a process of rolling, pressing and cooling, which forms the hollow body necessary, compacts the wall, causes the strength to resist bursting strain, and hardens the material by chilling.

My process is hereinafter more fully described in connection with the accompanying drawings, and the essential characteristics are summarized in the claims.

In the drawings, Figure 1 is a plan of a cannon produced by my invention; Fig. 2 is a view of the billet from which the cannon is made; Fig. 3 is a somewhat diagrammatic view representing the rolling of this billet by skew-placed rolls to render the billet hollow and elongated with a substantially tapered exterior; Fig. 4 is a longitudinal section through the apparatus in which the formed body is pressed and chilled; Fig. 5 is a cross section of Fig. 4 adjacent the 35 larger end thereof, as indicated by the line 5-5 on Fig. 4; Fig. 6 is a sectional elevation of a portion of the tubular plug which constitutes part of the apparatus shown in Fig. 4.

In performing the process of this invention, I take a substantially cylindrical billet, as shown at A in Fig. 2 and pass it between rolls B and B which are set with their axes at an angle to each other, and thus operate in a well known manner to gradually form a hollow bore in the billet and elongate it. Such an operation of rolling billets to render them tubular is shown and described, for instance, in Patent No. 361,954, granted April 26, 1887 to Max Mannesmann.

In order to give the exterior of the tubular body being formed a tapered or conical form, I provide subsequent pairs of rolls C, C which have skewed axes, but stand nearer each other than the rolls B. The number of pairs of these subsequent rolls

employed depends upon the amount of taper which is to be given to the body. This tapering feature by subsequent pairs of rolls is illustrated, for example, in Patent No. 60 361,961, granted April 26, 1887 to Max Mannesmann.

Having produced a tapered tubular body of approximately the form shown at A' in Fig. 3, I reheat it, if necessary, to bring it to a bright red heat, and place it within a heavy tapered mold, designated D. This mold may be of cast iron and consist of two longitudinal halves, each having a tapered trough-portion of semi-circular contour, 70 and to a certain extent closed at the ends and each provided with flanges by which the mold parts are secured together by bolts d'. When the billet is placed in this mold, I drive or otherwise force into the bore 75 thereof a tapered hollow plug or pipe E. This tapered pipe is of sufficient strength to force the metal outwardly and compact it between the exterior of the pipe and the wall of the mold, thus producing the conical 80 body shown at A², in Fig. 4.

The rolling of the billet to produce the original hollow center gives the fibers a general circumferential direction. This direction of the fibers may be somewhat lost in any 85 reheating, but it is restored and increased by the forcing in of the central tapered plug, which flattens the grains in a direction at right angles to the pressure, which is radially outward against the mold wall. It 90 is understood that the billet is closely embraced by this wall, so that the material of the body is necessarily compacted as the plug is forced into it. The result is that I have produced a tubular body of strong 95 compact material with its fibers extending circumferentially and thus best adapted to resist the bursting strain to which cannons are subjected.

The mold is preferably heated before the 100 billet is placed in it, while the pipe is driven or forced in cold. The result is that the cannon body is chilled first adjacent to the bore and cools more slowly from the outside, thus contracting it around the bore as a core. 105 The chilling may be further increased by supplying water to the interior of the plug E. To enable such water to flow through the plug, I preferably make the pointed end e of the plug removable, as illustrated in 110 Fig. 6, and when desired to use this artificial cooling I simply remove this end and

attach a hose to the larger end of the plug. The chilling does not harden the body sufficiently to prevent its being worked.

After the cannon body is formed, the exterior mold may be removed by unbolting the bolts d' . The interior plug may be either pressed out of the cannon body or it is left therein and removed by boring when the body is finally bored to size preceding rifling thereof.

The body may be made without trunnions, the trunnions being provided by a separate band shrunk onto the body, as is at present usual. Fig. 1 indicates the cannon after it has been finished. A^3 is the body generally and a the band carrying the trunnions a' . The cylindrical and rifled bore is indicated at a^3 , the enlarged bore for the shell at a^4 , and the chamber for the breech block at a^5 .

Having thus described my invention, what I claim is:

1. The process of making cannon, consisting of placing a hot tubular body in a surrounding mold, forcing a hollow tapered plug into the bore of the body, cooling the interior of the body by passing a cooling medium through the hollow bore in the plug, and thereafter removing the plug.

2. The process of making cannon, consisting of rolling a billet between skewed rolls to make a hollow body, placing such body in a mold, forcing a plug into the bore of the body to compact the material between the body and mold, and removing the plug from the body and the body from the mold.

3. The method of making cannon, consisting of rolling a billet to make a hollow body, placing such body while hot in a mold, forcing into the body bore of the mold a hollow plug, supplying water to the interior of the plug to cool the body, removing the body from the mold and boring a central bore into the body, the plug being removed.

4. The method of making cannon, consisting of rolling a billet to make a hollow

tapered body, placing such body while hot in a conical mold, forcing into the interior of the body a tapered plug which compresses the material of the body between the wall of the plug and the interior of the mold and causes the grains to flatten longitudinally and circumferentially, and thereafter boring out the center of the body cylindrically, the plug being removed.

5. The method of making cannon, consisting of rolling a billet between successive skewed rolls to produce a hollow tapered body, placing such body in a mold having a substantially conical interior, forcing into the body while in the mold and hot a hollow tapered plug, cooling the body by passing a cooling medium through the hollow of the plug, removing the body from the mold and the plug from the body and boring the material of the body and immediately outside of the plug to make a cylindrical bore which is subsequently rifled.

6. The method of making cannon, consisting of forming a hollow tubular body, placing the same while hot in a mold which surrounds the body and substantially incloses the ends thereof, forcing a tapered plug into the body, thereby compacting the body between the plug and mold wall, and there- after removing the plug.

7. The method of making cannon, consisting of rolling a billet to make a hollow tapered body, placing such body while hot in a mold which closely surrounds it and approximately incloses it at the ends, forcing a hollow tapered plug into the body to compact the material of the body, cooling the body by passing a cooling medium through the bore of the plug, removing the mold from the body and boring the body to a cylindrical bore larger than the plug, the plug being removed.

In testimony whereof, I hereunto affix my signature.

DARWIN B. CLEVELAND.
